(57) **CLAIM**

The ornamental design for a motor vehicle roof component, as shown and described.

DESCRIPTION

FIG. 1 is a plan view of motor vehicle roof component installed onto an environmental motor vehicle roof, showing our new design;

FIG. 2 is a perspective view thereof;

FIG. 3 is a plan view thereof;

FIG. 4 is a side elevation view thereof, the opposite side being a mirror image; and,

FIG. 5 is a perspective view thereof installed onto an environmental motor vehicle roof.

The broken lines showing the motor vehicle roof are provided for the purpose of illustrating environmental structure and form no part of the claimed design.
